UNITED STATES PATENT OFFICE.

MARK W. MARSDEN, OF PHILADELPHIA, PENNSYLVANIA.

SHOT RETARDING AND OBTURATING ELEMENT.

1,192,661.

Specification of Letters Patent. Patented July 25, 1916.

No Drawing.

Application filed November 6, 1915. Serial No. 60,054.

To all whom it may concern:

Be it known that I, MARK W. MARSDEN, a citizen of the United States, residing at Philadelphia, in the county of Philadelphia and State of Pennsylvania, have invented certain new and useful Improvements in Shot Retarding and Obturating Elements, of which the following is a specification.

This invention is a material suitable for 10 packing and obturating purposes, and as a defense or barrier for powder magazines, coast fortifications, &c., and as a shot-obstructing leak-stopping filler or core for the cofferdams or compartments of naval and 15 other vessels. The cellulosic materials now in general use for some of these purposes are expensive both as regards the raw material as well as the mode of treatment required to put the latter in condition to function; and 20 they are short-lived in the sense that they are deleteriously affected by moisture so that they become molded and decayed in which state they are worthless for plugging and shot-retarding purposes.

25 Hence it is an object of my present invention to provide a material suitable for packing, obturating or leak-stopping purposes, which shall be comparatively inexpensive, naturally fire and water proof, highly compressible, yielding and resilient, and possessed of great absorptive power.

Another object is to provide a material of the character stated, specially qualified as a shot-retarding element, which may not be 35 fired by the friction of projectiles or the explosion of the bursting charge thereof, and which is not deleteriously affected by dampness or by dry rot.

In experimenting with different materials 40 and combinations of materials I have discovered that mineral wool and asbestos when combined and in a state of compression, as hereinafter described, have all the advantages and lack the disadvantages of the cel- 45 lulosic materials.

To practise the invention mineral wool and asbestos are combined in the ratio of about 85 to 80 per cent. of mineral wool to about 20 to 15 per cent. of asbestos. Mineral 50 wool is cheaper than asbestos, but possesses a weaker fiber. However, when the two are combined and well commingled the longer fiber of the asbestos will interlace with, bind together, and strengthen the other or more 55 dense material. The mass of commingled

fibers is then condensed or subjected to considerable pressure, for example in a hydraulic press. For convenience in handling, the compressed mass in cube or other form may, if desired, be inclosed in a fire and wa- 60 ter proof wrapper.

The described material is not deleteriously affected by dampness or moisture, that is to say it will not mold or rot, is immune to dry rot, and moreover it is absolutely fire- 65 proof. On the other hand so-called fire and waterproof leak stoppers of vegetable origin not only deteriorate and decay when attacked by the local dampness or moisture that sweats through the inclosing walls, say 70 of a cofferdam, but are also susceptible of dry rot and spontaneous combustion, and are also fired by the friction of projectiles.

The obturating and shot-retarding material of my invention is naturally fireproof 75 and is water resistant in the sense that it will not deteriorate and lose its absorptive ability when attacked by dampness. Furthermore, when the inclosing walls are ruptured, for example by reason of collision or by penetra- 80 tion of a projectile, the material swells rapidly when attacked by the inrushing water, bursting its wrapper if one be employed, and the long fiber of the asbestos operates to prevent the shorter staple of the mineral wool 85 from washing away. Not only does this material form an admirable obturating ele- 90 ment, but it also, by reason of its density or high state of compression and consequent yielding and resilient qualities, constitutes 90 an efficient shot-retarder, barrier or obstruc- 95 tion.

A cheaper if not quite as effective product is obtained by employing in admixture with the mineral wool and asbestos a fiber or cel- 95 lulose of vegetable origin, for example that derived from bagasse. Of course in this case the bagasse or other additive would be fire and waterproofed before combining it with the natural ingredients.

Having described the nature and objects of the invention and the manner in which the same is to be performed, I claim:—

1. A shot-retarding and obturating ma- 105 terial possessed of marked yielding and re- sili- 105 ent and absorptive properties, consisting of a compressed mass of mineral wool and asbestos intermixed or matted together.

2. A shot-retarding and obturating ma- 110 terial possessed of marked yielding and resili-

ent and absorptive properties, consisting of a compressed mass of mineral wool, asbestos, and a fiber of vegetable origin primarily fire and waterproofed, said elements being 5 intimately commingled and matted together, substantially as described.

3. Material for the purposes stated, consisting of a highly absorptive yielding and resilient mat of more than fifty per cent.

mineral wool and less than forty per cent. asbestos.

In testimony whereof I affix my signature in presence of two witnesses.

MARK W. MARSDEN.

Witnesses:

ALLAN I. HUCKINS,
E. W. STRAIN.
